ASH HOPPER

Edgar B. Tolman, Winnetka, Ill., assignor to United Conveyor Corporation, a corporation of Illinois

Filed Apr. 16, 1958, Ser. No. 728,989

6 Claims. (Cl. 302—52)

This invention relates to an ash hopper, and in particular it relates to a hopper construction which may receive fly ash from a furnace and feed it into a vacuum conveyor system.

The huge quantities of very fine ash which are produced in a modern power plant coal burning boiler present serious handling problems. The material is inherently difficult to store and transport, because it is so fine that it packs almost into a solid mass in a hopper or storage vessel, and even flow of the ash is difficult to achieve because of the way it will arch, slump, and otherwise behave in a manner inimical to easy handling.

One of the most difficult pieces of equipment in which to obtain satisfactory ash flow is a standard hopper bottom, such as is found in a centrifugal separator or electrostatic precipitator, which has a tapered bottom portion terminating in an outfeed opening. As the hopper fills, the weight of ash packs the discharge opening and forms a solid mass between the converging walls of the lower portion of the hopper. If the hopper is provided with a conventional discharge gate, the opening of the gate may permit a small drop of ash from the area immediately above the hopper discharge opening; but the majority of material in the hopper will remain packed between the converging side walls.

In accordance with the present invention, the hopper is provided with generally horizontally disposed aerating devices of conventional construction which are positioned a substantial distance above the bottom of the tapered portion of the hopper. These aerating elements provide supporting shelves which prevent the weight of the ash above from packing the ash in the lower part of the hopper between the converging side walls. Each aerating element is provided with a source of low pressure air in the usual fashion, and this aerating air fluidizes the ash so that it may flow freely down through the hopper and out the bottom discharge opening.

Secured to the bottom of the hopper, to receive ash through the discharge opening, is an aerating chamber which has an inclined aerating floor and a discharge orifice of relatively small size the lower side of which is flush with the lower end of the aerating floor.

Discharge of ash from the hopper may occur in a smooth, even flow, without arching or slumping of the ash in the hopper, and with no packing of ash between the converging side walls of the lower portion of the hopper.

When a sufficient amount of ash has been released from the hopper the flow of aerating air may be stopped; and this will stop the feed of ash out of the hopper so that the vacuum conveyor conduit into which the hopper feeds the ash may receive ash from another hopper or hoppers in a large system.

The invention is illustrated in a preferred and an alternative embodiment in the accompanying drawings in which:

Fig. 1 is a vertical central sectional view of the preferred embodiment of the invention;

2

Fig. 2 is a section taken substantially as illustrated along the line 2—2 of Fig. 1;

Fig. 3 is a vertical central sectional view of an alternative embodiment of the invention;

Fig. 4 is a section taken substantially as illustrated along the line 4—4 of Fig. 3.

Referring to the drawings in greater detail, and referring first to Figs. 1 and 2, the lower part 9 of an ash collecting device has a continuous, upright wall portion 10 which merges at its lower end into a frusto-pyramidal bottom portion, indicated generally at 11, the converging walls of which are numbered, 12, 13, 14 and 15. At the bottom of the hopper body is an outfeed opening 16 of relatively small width and area. Extending downwardly from the hopper body beneath opening 16 is an outfeed throat 17 communicating with an aerating chamber, indicated generally at 18. Aerating chamber 18 is provided with an aerating floor 19 which is pitched toward an upright partition 20 in which there is a discharge orifice 21 by means of which aerating chamber 18 communicates with a discharge throat 22 leading to a vacuum conveyor conduit (not shown). Aerating floor 19 is of conventional porous construction, so that air entering a plenum chamber 23 below the aerating floor from a low pressure air line 24 may diffuse through the floor 19 and aerate, or fluidize ash in aerating chamber 18. Since several hoppers like the hopper here disclosed are ordinarily used to feed a single vacuum conveyor conduit, each aerating chamber is provided with a shut off valve mechanism 25 for closing the discharge orifice 21 when the hopper 9 is empty.

The aerating chamber 18 affords smooth flow of fluidized ash which has passed through the outfeed opening 16 of the hopper; but the converging side walls of the frusto-pyramidal bottom portion of the hopper cause difficulty in the feed of ash through the relatively restricted outfeed opening 16. In accordance with the present invention, the frusto-pyramidal bottom portion 11 of the hopper is provided with aerating means, indicated generally at 26, which includes a pair of generally horizontal aerating shelves 27 and 28 extending inwardly from the side walls 12 and 13, respectively, of the hopper body, a substantial distance above outfeed opening 16. The aerating shelves 27 and 28 act as supports for ash in the hopper 9, to prevent it from packing between the converging side walls of the hopper, and since each of the shelves is an aerating element it may be used to fluidize the ash which is supported on it, so that the ash flows freely toward the outfeed opening 16. As seen in Fig. 1, aerating shelf 27 is mounted above shelf 28, and the inner edges 27a and 28a of the shelves overlap so that ash may flow from shelf 27 onto shelf 28, and thence to outfeed opening 16.

Aerating air for the shelves 27 and 28 is provided, respectively, by air lines 29 and 30 which, together with line 24 for aerating floor 19, are fed from a single low pressure air line 31.

If desired, hopper 9 may be provided with a vertical baffle 32 which extends transversely of aerating shelves 27 and 28, in order to divide the flow of ash through the hopper.

Referring now to Figs. 3 and 4, the construction of the ash hopper 9 and the aerating chamber 18 are identical with the form of device just described, so that these components will not be described in detail; and their various elements are given reference numerals identical to those in the form just described.

In this form of device, the aerating means in the bottom portion 11 of the hopper is indicated generally at 126, and includes generally horizontal, coplanar aerating shelves 127 and 128 which extend inwardly from the side walls 12 and 13, respectively, of the hopper body, a sub-

stantial distance above outfeed opening 16. The aerating shelves 127 and 128 act as supports for ash in the hopper 9, to prevent it from packing between the converging side walls of the hopper, and since each of the shelves is an aerating element it may be used to fluidize the ash which is supported on it, so that the ash flows freely toward the outfeed opening 16. As seen in Fig. 3, the inner edges 127a and 128a of the aerating shelves 127 and 128 are spaced apart to provide an opening 133 which is directly above outfeed opening 16. In the illustrated embodiment, the space between the shelves is narrower than the outfeed opening 16; but it is obvious that the only limit on the width of the space 133 is that it shall not be substantially wider than outfeed opening 16, so that the aerating shelves 127 and 128 may occupy a major part of the width of the hopper.

Aerating air for the shelves 127 and 128 is provided, respectively, by air lines 129 and 130 which, together with a line 24 for the aerating floor 19 of the aerating chamber 18, are fed from a single low pressure air line 31.

If desired, hopper 9 may be provided with a vertical baffle 132 which extends transversely across the two aerating shelves 127 and 128, in order to divide the flow of ash through the hopper.

The foregoing detailed description is given for clearness of understanding only and no unnecessary limitations are to be understood therefrom, as modifications will be obvious to those skilled in the art.

I claim:

1. An ash hopper comprising: a hopper body which tapers toward its lower end and has a bottom outfeed opening of relatively small width and area; upper aerating means including a plurality of generally horizontal aerating shelves extending inwardly from the sides of the hopper body a substantial distance above said outfeed opening to support and fluidize ash for free flow to and through said opening; an aerating chamber secured to the bottom of the hopper body to receive ash therefrom, said chamber having a discharge orifice at one end; and a floor in said chamber provided with aerating means to fluidize ash for free flow through the discharge orifice.

2. The device of claim 1 in which the aerating shelves are in a single plane with a space between the inner margins of opposite shelves which is not substantially greater than the width of the outfeed opening.

3. The device of claim 1 in which the aerating shelves

are on opposite sides of the hopper body and are vertically spaced with their inner edges overlapping so that fluidized ash may flow from one shelf to another.

4. An ash hopper comprising: a hopper body the upper portion of which has substantially vertical walls, and the lower end portion of which has uninterrupted inclined walls converging to a bottom outfeed opening of relatively small width and area, said uninterrupted converging walls tending to compact ash adjacent the outfeed opening and thus inhibit its free flow through said opening; a plurality of generally horizontal shelves extending inwardly from said converging walls of the lower end of the hopper body a substantial distance above said outfeed opening, each of said shelves having its inner margin not substantially farther from the vertical axis of the hopper than a vertical plane through the adjacent margin of the outfeed opening, so that ash may flow off the inner margin of each shelf into a space substantially directly above said opening, said shelves cooperating to support ash in the hopper and minimize the compacting effect of the uninterrupted converging walls; aerating means on each shelf to fluidize the ash above said shelf and thereby promote free flow of ash from all said shelves to and through the outfeed opening; an aerating chamber secured to the bottom of the hopper body to receive ash therefrom, said chamber having a discharge orifice at one end; and a floor in said chamber provided with aerating means to fluidize ash for free flow through the discharge orifice.

5. The device of claim 4 in which the shelves are in a single plane, and the distance between inner margins of opposite shelves is not substantially greater than the width of the outfeed opening.

6. The device of claim 4 in which there are two coplanar shelves on opposite sides of the hopper body, and the distance between their inner margins is not substantially greater than the width of the outfeed opening.
